UNITED STATES PATENT OFFICE

156,479

VISOR FOR AUTOMOBILE WINDSHIELDS

Robert E. Bingman, Detroit, Mich., assignor to
Charles Peckat Manufacturing Co., a corpora-
tion of Illinois

Application June 8, 1948, Serial No. 146,830

Term of patent 3½ years

(Cl. D14—6)

To all whom it may concern:

Be it known that I, Robert E. Bingman, a citizen of the United States, residing at Detroit, in the county of Wayne and State of Michigan, have invented a new, original, and ornamental Design for a Visor for Automobile Windshield, of which the following is a specification forming part thereof.

Figure 1 is a top plan view of a visor for automobile windshield embodying my new design;

Figure 2 is a rear elevational view; and

Figure 3 is a side elevational view thereof.

The several figures of the drawing have been shaded to show contrasting appearance.

The characteristic features of my design re-

side in the portions shown by means of full lines in the drawing.

I claim:

The ornamental design for a visor for automobile windshield, as shown and described.

ROBERT E. BINGMAN.
